Primary Examiner — Catherine Tuttle(74) *Attorney, Agent, or Firm* — Joseph W. Staley; Katherine D. Buchanan**CLAIM**

The ornamental design for a toy ball, substantially as shown and described.

DESCRIPTION

FIG. 1 is a perspective view of a toy ball, embodying the new design;

FIG. 2 is a top view of the toy ball of FIG. 1;

FIG. 3 is a front view of the toy ball of FIG. 1, the rear view being substantially identical thereto;

FIG. 4 is a bottom view of the toy ball of FIG. 1; and,

FIG. 5 is a first side view of the toy ball of FIG. 1, the opposite side being substantially identical thereto.
